UNITED STATES PATENT OFFICE.

HENRY HUGO, OF HOLTVILLE, CALIFORNIA.

COUNTER-STOOL CONSTRUCTION.

Application filed March 21, 1922, Serial No. 545,482. Renewed June 25, 1924.

To all whom it may concern:

Be it known that I, HENRY HUGO, a citizen of the United States, residing at Holtville, in the county of Imperial and State of California, have invented new and useful Improvements in Counter-Stool Construction, of which the following is a specification.

The object of my said invention is the provision of a counter-stool construction in which the stool or stools permanently connected with the counter are adapted to be raised from the floor and positioned as when the floor is to be cleaned and may then be expeditedly and easily replaced in working position.

To the attainment of the foregoing, the invention consists in the improvement as hereinafter described and definitely claimed.

20 In the accompanying drawings, forming part of this specification:—

Figure 1 is an end elevation showing a portion of a counter equipped with my improvement, the stool shown being in working position.

Figure 2 is an elevation at right angles to Figure 1, with one stool in working position and the other in raised idle position.

Figure 3 is a view like Figure 1 but with 30 the stool in raised and idle position.

Figure 4 is a front elevation of a modification.

Figure 5 is an end elevation of the same.

Figure 6 is an end elevation of another modification.

Figure 7 is an enlarged detail horizontal section taken in the plane indicated by the line 7—7 of Figure 6.

Figure 8 is a detail horizontal section on the line 8—8 of Figure 1.

Similar numerals designate corresponding parts in Figures 1, 2, 3 and 8 to which reference will first be made.

In accordance with my invention a foot-rail 1, of circular form in cross-section is connected with and maintained in spaced relation to the lower portion of a counter 2, the connection being effected by brackets 3 fixed to the counter 2 and carrying the rail.

50 Mounted on the rail 1 to turn about the same are pairs of short sleeves 4 and 5, there being a pair of sleeves 4 and a pair of sleeves 5 employed in combination with each stool. The stools respectively comprise a standard rod 6, a seat 7 at the upper end of

said rod, a base 8 at the lower end of the rod, and a pad 9, of rubber or other appropriate cushioning material, at the underside of the base.

The standard rod 6 of each stool is slidably arranged in upper and lower collars 10 and 11, the upper collar 10 having a bifurcated projection 12, Figure 8, in which are pivotally connected at 13 the upper ends of downwardly-divergent arms 14, integral 65 with or fixed to the sleeves 5, and the lower collar 10 being similarly connected with downwardly divergent arms 15, integral with or fixed to the sleeves 4.

In virtue of the construction described, 70 it will be manifest that when a stool is arranged upright on a floor, designated by 16, as shown in Figure 1 and at the left of Figure 2, the stool will be strongly held against casual lateral movement and will constitute 75 a strong and stable seat. It will also be manifest that when it is desired to scrub, mop or otherwise clean the floor in the vicinity of the counter any one of the stools may be swung upwardly and toward the counter 80 2 into the position shown at the right of Figure 2 and in Figure 3 in which position the padded base 8 will rest on the rail 1 and the seat 7 will rest against the face of the counter and the stool as a whole will be 85 maintained off the floor and out of the way. After the completion of the floor-cleaning operation each of the stools obviously may be quickly and easily moved from the position shown in Figure 3 to the working position shown in Figure 1.

In the modification shown in Figures 4 and 5 the construction is the same as in Figures 1, 2, 3 and 8 except that a short individual rail 1^a connected by brackets 3^a to the counter 1 is employed in conjunction with each stool and the appurtenances thereof. The said modification of Figures 4 and 5 is possessed of all the capacity of function ascribed to the embodiment in Figures 100 1 to 3 and 8.

According to the modification shown in Figures 6 and 7, the standard rod 6 of a stool such as before described is arranged in collars 10^a and 11^a, each of the said collars carrying a set screw 17 to engage the standard rod 6, and each having a projection 18 with a transverse aperture 19 therethrough to receive a headed and threaded bolt 20 on which is a wing nut 21. The up- 105 110

per bolt 20 is arranged in the slotted upper portions 22 of downwardly-divergent arms 14^a similar to the before described arms 14 and similarly connected to a rail 1, and the 5 lower bolt 20 is arranged in the slotted upper portions 23 of downwardly-divergent arms 15^a similar to the before described arms 15 and similarly connected to the rail 1. The portion of each bolt 20 adjacent to the 10 head thereof and which portion is arranged in the slot of one of the said arms is of angular form in cross-section as indicated by 24 in Figure 7, this provision being made in order to prevent the bolts turning about 15 their axes.

In the use of the construction shown in Figures 6 and 7 it will be seen that when the set screws 17 are set against the standard rod 6, and the wing nuts 21 are tightened, the stool will be secured in the position shown in Figure 6 and against movement toward the counter 2. It will also be understood that when the set screws 17 and the wing nuts 21 are loosened the stool may be 20 moved upwardly and toward the counter and so that the base 8 may be supported on the rail 1, between the divergent arms 11^a.

For convenience of assembly, the bases 8 in all of the embodiments shown and described, are preferably threaded on or otherwise detachably connected to the lower ends of the standard rods 6.

It will be apparent from the foregoing that in addition to the advantages ascribed 35 to the embodiments shown and described each of the same is simple and inexpensive in construction and is susceptible of being so made and embellished as to enhance

rather than detract from the finished appearance of a counter with which it is associated. 40

I have entered into a detailed description of the construction and relative arrangement of the parts embraced in the present and preferred embodiments of my invention 45 in order to impart a full, clear and exact understanding of the said embodiment. I do not desire, however, to be understood as confining myself to the said specific construction and relative arrangement of parts inasmuch as in the future practice of the invention various changes and modifications 50 may be made such as fall within the scope of my invention as defined in my appended claim. 55

Having described my invention, what I claim and desire to secure by Letters-Patent, is:—

The combination of a counter, a horizontally disposed rail connected with and spaced therefrom, a stool having a standard rod in front of and extending above and below the rail and a base at the lower end of said rod and a seat at the upper end of the rod, and vertically-swinging means connecting said standard rod and said rail, said means having a sliding connection at one end with the rod, whereby said rod may have an upwardly sliding movement within this end of said means, the said stool being movable from a position in which its base rests on a floor to a position with its seat edge against the counter and with its base superimposed on the rail. 60 65 70

In testimony thereof, I affix my signature.
HENRY HUGO.
